PROCESS OF AND APPARATUS FOR TREATING BADMINTON SHUTTLECOCKS

Donovan Hoult Pollitt, Leaside, Ontario, Canada,
assignor to Pennsylvania Rubber Company, a
corporation of Pennsylvania

Application December 24, 1940, Serial No. 371,554
In Canada July 9, 1940

3 Claims. (Cl. 91—46)

This invention relates to treating badminton shuttlecocks. Badminton shuttlecocks consist of a head and a vane, generally speaking. The vane usually consists of a plurality of feathers the quills of which are inserted in holes arranged around the periphery of the inner or upper face of the head. The quill portions of the feathers are joined by two or more rows of stitching, and lacquer or adhesive is brushed onto the quill part of the feathers and the stitching. The lacquer or adhesive reinforces and protects the quills and stitching, retains the stitching in position, and bonds or cements the quills in the holes in the head. By the usual brushing method, however, it is impossible to apply the lacquer or adhesive evenly and uniformly and the process is slow because each individual shuttlecock must be treated by hand. Nor is it practical to apply by brush a lacquer or cement of a viscosity that will penetrate all the interstices between the stitching and the quills and the crevices between the quills and the head. The object of my invention is to devise a process whereby the adhesive or lacquer may be quickly and evenly applied in such a manner that it will enter the interstices between the stitching and the quills and the crevices between and adjacent to the quills and the sides of the holes in the head, and thus obtain an effective bond or union of all component elements of the shuttlecock and a flexible durable coating on that portion of the feathers likely to come in contact with the racquet during the course of play.

The object of this invention is attained by inserting the head of the shuttlecock in an open-ended masking ring one end of which fits in air-tight contact with the inner end of the head, the other end of which extends beyond the outer end of the head, and dipping the shuttlecock head first in a treating liquid to such depth that the masking ring is completely immersed and the liquid flows over the head and around the vane of the shuttlecock to the desired extent and for sufficient time to permit of complete saturation of the parts.

It is an important feature of the invention that a less viscous liquid may be used in this process than in brushing, so that a more even coating and a more thorough degree of saturation is obtained. By permitting the initial coating to dry and then redipping a very even, durable, and resilient coating is effected.

The invention is hereafter more particularly described and is illustrated in the attached draw-

ing from which further details thereof may be obtained:

Figure 1 is a longitudinal section of a shuttlecock with masking ring and handle attached thereto ready for dipping;

Figure 2 is a diagrammatic plan view of a treating tank showing a rack supported thereabove in position for draining;

Figure 3 is a side view partly broken away of 10 a treating tank showing the rack in position for dipping the shuttlecock and in dotted lines in raised position for draining; and

Figure 4 a diagrammatic perspective view 15 partly broken away showing a shuttlecock in position in an arbor press for removing the same from the masking ring.

Corresponding numerals in the different figures refer to corresponding parts.

In Figure 1 is shown a shuttlecock comprising 20 a substantially semi-cylindrical cork head 10 and a vane 11 consisting of a plurality of feathers the quill portions of which are inserted in holes extending around the periphery of the head 10. The barbs have been shorn from the quills for a 25 certain distance from the ends of the feathers above the head of the shuttlecock and two rows of stitching 11a extend around and between the quills. The stitching strengthens the quills and maintains them in proper relative position.

To treat the quills with adhesive or lacquer 30 an open-ended masking ring or collar 12 of slightly smaller diameter than the inner or upper end of the head is forced over the head as illustrated in Figure 1. The diameter of the masking collar 12 is such as to slightly compress the cork of which the head is made and provide an air-tight contact therewith.

The head is provided with a central aperture 10a, which in the finished shuttlecock contains a 40 weight of lead or similar suitable material. This weight is usually added after the shuttlecock as a whole has been otherwise completed, as described in Canadian Patent No. 343,728, granted to me August 7, 1934. At the stage of manufacture with which the present invention is concerned the hole 10a is open and empty, and a dipping handle 13 having a reduced threaded end portion 13a is screwed into the said hole 10a. The diameter of the body of the rod which forms 45 the dipping handle is preferably considerably greater than the diameter of the threaded end portion, so that a shoulder is formed which is adapted to engage the inner face of the head when the handle is screwed in place and keep a portion of the head free of the treating liquid.

50

The dipping handle 13 may be grasped and the shuttlecock dipped head first into a treating liquid to such depth that the masking ring is completely immersed and the liquid flows over the head and around the quills of the feathers to the desired extent. Ordinarily the feathers are treated up to and slightly above the shorn parts of the quills. In practice the shuttlecock will be left in the adhesive or lacquer a suitable period to effect complete saturation. The air trapped in the ring 12 will prevent the liquid from entering the ring and contacting the outer end of the head. The liquid will completely cover the quills, the stitching, and the outer edges of the upper or inner face of the head and will fill and/or cover any spaces that there may be between the quills and the head of the shuttlecock at the points where the quills enter the head.

After the shuttlecock has been removed from the liquid a spray of compressed air from a nozzle 14 (Fig. 3) is directed against it to remove excess liquid, leaving a thin even film. The shuttlecock, with the masking ring still attached thereto may be permitted to dry either at ordinary room temperature or in a special drier, and may be again dipped and dried. A much less viscous material may be used for dipping than for brushing, with the result that the shuttlecock may be dipped twice or more to produce a coating of equivalent thickness, but more even, penetrant, resilient and durable.

When the shuttlecock is dry the masking ring 12 may be quickly and easily removed by means of an ordinary arbor press (Fig. 4) having a support 15 for the masking ring 12 and a punch 16 adapted to enter the open end of the ring 12 and engage the outer end of the head 10 and force it back out of the ring.

For commercial work a plurality of dipping handles 13 will be secured to a rack 18 which consists of a frame and a plurality of cross-pieces 18^a on which the handles 13 are mounted as illustrated in Figures 2 and 3.

Figure 3 is a diagrammatic illustration of the method of dipping by means of the rack. The shuttlecocks and masking rings are mounted on the handles 13 in the way already described, and the frame 18 is inverted over a tank 19, the edges of the frame resting on the edges of the tank or on special supports therefor (not shown). The level of the liquid 20 in the tank is maintained by means of a supply tank 21 and a feed pipe 22 in which is located a float valve 23.

At each corner of the tank 19 is a post 19^a on which are supports 24 pivotally mounted on pins 25 and engaging stops 26 to hold them in outwardly extending rack-supporting position. The supports 24 are swung back into the position illustrated in dotted lines in Figure 3, when the tray is mounted on the tank 19 for immersing the shuttlecocks in the liquid 20. They are then swung back to the supporting position and when the tray is lifted up it engages the supports 24 and pushes them up sufficiently to permit the

tray to be carried past the supports. The tray is then dropped on to the supports which hold it in an elevated position above the tank to permit the lacquer to dry, the excess liquid dripping into the tank. In this position the spray of air may be applied thereto.

While the conventional construction of shuttlecock has been described, it will be understood that the invention would be applicable to shuttlecocks in which the vane is composed of material other than feathers. For purposes of ornament or identification colored lacquers may be used instead of the ordinary white or colorless lacquer or adhesives.

The applicant does not desire to be limited to the specific process and apparatus described and illustrated by way of example.

I claim as my invention:

1. A step in the production of a badminton shuttlecock which consists in inserting the head of a head-and-vane assembly in an open-ended, cylindrical, masking ring of rigid material of greater length than such head, with compression of the substance of the head into air-tight contact with the ring, the ring extending beyond the outer end of the head, dipping the assembly head first in a bath of coating liquid with immersion of the ring-encircled head and of the base of the vane and with the trapping within the outer end of the ring and upon the outer end of the head of a protective body of air, removing the assembly from the bath, and driving the coated article from the ring by pressure exerted through the open end of the ring upon the outer end of the head.

2. A step in the production of a badminton shuttlecock which consists in inserting the head of a head-and-vane assembly in an open-ended, cylindrical, masking ring of rigid material of greater length than such head, with compression of the substance of the head into air-tight contact with the ring, the ring extending beyond the outer end of the head, securing removably to the head through its inner face a dipping handle, dipping the assembly by means of the dipping handle head first in a bath of coating liquid with immersion of the ring-encircled head and of the base of the vane and with the trapping within the outer end of the ring and upon the outer end of the head of a protective body of air, removing the assembly from the bath, and freeing the coated article from the dipping handle and from the masking ring.

3. Apparatus for dipping shuttlecocks including a handle and a ring adapted to be assembled with a shuttlecock to constitute a unit for dipping, the handle being equipped with means for securing it to the head of the shuttlecock through the rear surface thereof, and the ring being adapted to receive the head of the shuttlecock compressed to air-tight union in its bore and being of a length exceeding the length of the head of the shuttlecock.

DONOVAN HOULT POLLITT.
